UNITED STATES PATENT OFFICE.

LONGHAIR I. MINATO, OF PLANO, IDAHO

SHOE-POLISHING MACHINE.

974,585.

Specification of Letters Patent.

Patented Nov. 1, 1910.

Application filed May 25, 1910. Serial No. 563,355.

To all whom it may concern:

Be it known that I, LONGHAIR INAS MINATO, a subject of the Emperor of Japan, residing at Plano, in the county of Fremont and 5 State of Idaho, have invented new and useful Improvements in Shoe-Polishing Machines, of which the following is a specification.

This invention relates to shoe polishing 10 machines of that type in which an endless band or belt is utilized for polishing the shoes.

The invention has for one of its objects to improve and simplify the construction and 15 operation of machines of this character so as to be comparatively simple and inexpensive to manufacture, reliable and efficient in use, and capable of being readily manipulated.

Another object of the invention is the provision of a machine which can be operated 20 by one foot while the shoe on the other foot is being polished.

A further object is the employment of novel operating means for the polishing 25 belt or band and for maintaining the proper tension thereon.

A further object is the provision of an adjustable foot rest disposed in co-operative relation with the band so that the shoe engaged with the rest can be effectively polished.

With these objects in view and others, as will appear as the description proceeds, the invention comprises the various novel features of construction and arrangement of parts which will be more fully described hereinafter and set forth with particularity in the claims appended hereto.

In the accompanying drawings, which 40 illustrate one embodiment of the invention, Figure 1 is a vertical section taken centrally through the machine. Fig. 2 is a vertical section taken parallel with the front of the machine. Fig. 3 is a horizontal section on line 3-3, Fig. 1. Fig. 4 is a detail view of the means for raising and lowering the shoe rest. Fig. 5 is a detail sectional view on line 5-5, Fig. 2.

Similar reference characters are employed 50 to designate corresponding parts throughout the views.

Referring to the drawings, A designates a supporting framework or other suitable structure which supports the various parts of the machine. At the bottom of the machine is a horizontal shaft 1 extending parallel with the front of the frame and on which is mounted a treadle 2, which is connected by a pitman 3 with a crank arm 4 on a rotary shaft that is mounted in bearings 6 55 adjacent the top of the frame and near the rear thereof. On this shaft 5 is a miter gear 7 which meshes with the miter gear 8 on the rear end of a transversely-extending horizontal shaft 9 which serves to impart power 60 to the polishing belt driving means. By the oscillation of the treadle 2, the crank and pitman connection will cause continuous rotation of the shafts 5 and 9, and as the result, the belt will be driven continuously in 70 one direction.

The polishing belt or band B passes around driving rolls 10 mounted in bearings 11 at the ends of the frame immediately at the top thereof, and from these rolls the 75 band extends inwardly and upwardly to pass under idler rolls 13 which are disposed at opposite sides and below the foot rest C, over which the top flight of the belt extends. The driving rolls 10 are provided with 80 sprocket wheels 14 which mesh with a sprocket chain 15 that receives power from a sprocket wheel 16 fastened to the forward end of the shaft 9. The idler rolls 13 may be movably mounted so as to maintain the 85 proper tension on the belt or band B. For this purpose, the ends of the rolls 13 are journaled in slides 17 which move back and forth in guideways 18 formed on the top of the frame and extending along the 90 front and rear thereof. Interposed between the outer ends of these guideways and slides are helical springs 19 which urge the slides inwardly so as to maintain the proper tension on the belt when the shoe is placed on 95 the rest C. The slides 17 are movably held in the guideways by bolts 20 passing through the base portion of the slides and extending loosely through slots 21 in the guideways.

The foot rest C is mounted in such a manner that it can be raised or lowered, according to the size of the foot and convenience.

of the user. Accordingly, the rest is mounted on a centrally-disposed horizontal support or bar 22 which has at its ends depending members 23 which move in vertically-disposed tubular guides 24 fastened to the frame of the machine at the front and rear thereof. On the members 23 are rack teeth 25 with which mesh pinions 26 fastened to a shaft 27 journaled in bearings 28 on the frame, and on the front end of this shaft is an operating crank or handle 29 that is provided with a ratchet wheel 30 engaged by a spring pawl 31 fastened on the frame, so that the crank can be readily turned to raise or lower the foot rest to any position of adjustment, and when the crank ceases turning, the spring pawl will hold the parts locked. If desired, the foot rest can be moved back and forth to present different portions of the shoe to the polishing belt or band. On the support 22 is arranged a longitudinal guideway 32 in which is slidably mounted a plate 33 that carries the foot rest. This plate can slide back and forth in the guideway 32 and will be held in any position of adjustment by a spring 34 disposed in the guideway 32 to frictionally engage the plate 33. It might be desirable to pivotally mount the foot rest for the purpose of allowing the shoe to be partially turned around so that the belt can reach the heel portion, and in this case, a socket-carrying stem 35 will be formed on the slide 33 to receive a ball 36 on the bottom of the rest.

In using the machine, a shoe to be polished will be supplied with blacking or polishing paste by a suitable dauber, and the shoe thus prepared, is placed on the foot rest C with the belt B extending over the shoe. The foot rest will be properly adjusted by turning the crank 29 so that the desired tension will be imparted to the belt. The treadle is now operated so as to cause the belt to pass over the shoe and polish the surface thereof, the foot being moved back and forth and turned from side to side as the belt continues to operate so that all portions of the shoe will be polished. It will be preferable for the user of the machine to seat himself in a chair so that one foot can be used for operating the machine while the shoe on the other foot is being polished.

From the foregoing description, taken in connection with the accompanying drawings, the advantages of the construction and of the method of operation will be readily apparent to those skilled in the art to which the invention appertains, and while I have described the principle of operation of the invention, together with the apparatus which I now consider to be the best embodiment thereof, I desire to have it understood that the apparatus shown is merely illustrative, and that such changes may be made

when desired as are within the scope of the 65 claims appended hereto.

Having thus described the invention, what I claim is:-

1. A machine of the class described comprising a supporting frame, an endless polishing band, operating means for the band, a vertically adjustable support, a slide movable on the support, a foot rest disposed above the slide and under the upper flight of the band, and a universal joint between 75 the foot rest and slide.

2. A machine of the class described comprising a supporting structure, a foot rest thereon, an endless polishing element having its upper flight extending transversely over 80 the rest, means for supporting and operating the element, idlers engaging the upper flight of the element at opposite sides of and below the rest, horizontally-movable devices on which the idlers are supported, horizontal alining guides in which the devices slide, and yielding means pressing the devices toward each other for tensioning the polishing element on the shoe supported by 85 the rest.

3. A machine of the class described comprising a supporting structure, an endless polishing band, a foot rest disposed to support a shoe in co-operative relation with the band, means for mounting the foot rest for 95 movement back and forth with respect to the band, and means for adjusting the vertical position of the foot rest.

4. A machine of the class described comprising a supporting structure, an endless 100 polishing band, driving rolls around which the band passes, a sprocket and chain mechanism for driving the rolls, a foot-operated device for actuating the said mechanism, spring-pressed idlers engaging the top flight 105 of the band, and an adjustable foot rest disposed above and between the idler rolls and under the active portion of the band.

5. A machine of the class described comprising a supporting structure, an endless 110 polishing band, driving rolls around which the band passes, a mechanism for driving the rolls, a device for actuating the said mechanism, idlers engaging over the top flight of the band, an adjustable foot rest 115 disposed above and between the idler rolls and under the active portion of the band, yielding means for pressing the idlers inwardly toward each other and toward the rest, and means for raising and lowering the 120 foot rest.

6. A machine of the class described comprising a supporting structure, an endless polishing band, driving rolls around which the band passes, a sprocket and chain mechanism for driving the rolls, a foot-operated device for actuating the said mechanism, spring-pressed idlers engaging the top flight 125

of the band, an adjustable foot rest disposed above and between the idler rolls and under the active portion of the band, means for raising and lowering the foot rest, and means for permitting the foot rest to be moved back and forth under the active portion of the band.

In testimony whereof I affix my signature in presence of two witnesses.

LONGHAIR I. MINATO.
